CLAIM

The ornamental design for a dimpled beverage dispenser, as shown and described.

DESCRIPTION

FIG. 1 is a top, front, and right-side perspective view of a dimpled beverage dispenser showing our new design; FIG. 2 is a front end elevation view thereof; FIG. 3 is a rear end elevation view thereof; FIG. 4 is a right-side elevation view thereof; FIG. 5 is a left-side elevation view thereof; FIG. 6 is a top view thereof; and, FIG. 7 is a bottom view thereof.

The broken lines showing a handle, lid, optional additional dimples and bottom details in conjunction with the dimpled beverage dispenser are provided for the purpose of illustrating environmental structure and forms no part of the claimed design.

1 Claim, 7 Drawing Sheets(56)
